US00D768916S

(12) United States Design Patent (10) Patent No.: US D768,916 S
Jordan et al. (45) Date of Patent: * Oct. 11, 2016

(54) ELECTRONIC VAPING DEVICE

(71) Applicants: Geoffrey B. Jordan, Midlothian, VA (US); Sean Sundberg, Richmond, VA (US); Bipin Patil, Richmond, VA (US); Charles Dendy, Richmond, VA (US)

(72) Inventors: Geoffrey B. Jordan, Midlothian, VA (US); Sean Sundberg, Richmond, VA (US); Bipin Patil, Richmond, VA (US); Charles Dendy, Richmond, VA (US)

(73) Assignee: Altria Client Services LLC, Richmond, VA (US)

() Term: 15 Years

(21) Appl. No.: 29/531,427

(22) Filed: Jun. 25, 2015

(51) LOC (10) Cl. 27-01

(52) U.S. Cl.

USPC D27/101

(58) Field of Classification Search

USPC ..... D3/20; D13/107, 118, 119, 184; D19/23, 115; D27/100, 101, 162, 170, D27/175, 183, 186, 187, 189, 193, 194 CPC A24F 47/008; A24F 47/002; A24F 15/18; A24F 13/02; A24F 13/06; A24F 15/00; A24F 7/04

(57) CLAIM

The ornamental design for an electronic vaping device, as shown and described.

DESCRIPTION

FIG. 1 is a rear perspective view of the electronic vaping device;

FIG. 2 is a rear view of the electronic vaping device;

FIG. 3 is a front view of the electronic vaping device;

FIG. 4 is a side view of the electronic vaping device;

FIG. 5 is a top view of the electronic vaping device;

FIG. 6 is a bottom view of the charger with electronic vaping device; and,

FIG. 7 is a front perspective view of the electronic vaping device.

In the drawings, the broken lines depict environmental subject matter only and form no part of the claimed design.

1 Claim, 4 Drawing Sheets
